UNITED STATES PATENT OFFICE.

FRANK R. MILLER, OF EVANSVILLE, INDIANA, ASSIGNOR TO THE GRAHAM GLASS COMPANY, OF EVANSVILLE, INDIANA, A CORPORATION OF INDIANA.

DESIGN FOR A BOTTLE.

Application filed February 20, 1926. Serial No. 16,627. Term of patent 14 years.

To all whom it may concern:

Be it known that I, FRANK R. MILLER, a citizen of the United States, residing at Evansville, in the county of Vanderburg and State of Indiana, have invented a new, original, and ornamental Design for Bottles, of which the following is a specification.

Referring to the accompanying drawings: Figure 1 is an elevation view of a bottle, showing my new design.

Figure 2 is a top plan view of the same.

Figure 3 is a sectional plan view of the same, the section being taken at the plane of the line III—III on Figure 1.

I claim:

The ornamental design for a bottle, substantially as shown.

Signed at Evansville, in the county of Vanderburg and State of Indiana, this 15th day of February, 1926.

FRANK R. MILLER.
